(57) **CLAIM**

The ornamental design for a container for cosmetic products,
as shown and described.

DESCRIPTION

FIG. 1 is a top, perspective view of a container for cosmetic products, showing my new design;

FIG. 2 is a side elevational view thereof, the opposite side
being a mirror image thereof;

FIG. 3 is a bottom perspective view thereof;

FIG. 4 is a top plan view thereof;

FIG. 5 is a bottom plan view thereof;

FIG. 6 is a side elevational view thereof, the container for
cosmetic products being in an alternate position;

FIG. 7 is a top, perspective view in a further alternate
position;

FIG. 8 is a side elevational view of the position shown in
FIG. 7, the opposite side being a mirror image thereof;

FIG. 9 is a bottom perspective view thereof;

FIG. 10 is a top plan view thereof; and,

FIG. 11 is a bottom plan view thereof.
